UNITED STATES PATENT OFFICE.

WILLIAM E. FICKLEN, OF NEW YORK, N.

CURB-NOSING AND THE LIKE.

1,032,393.

Specification of Letters Patent. Patented July 16, 1912.

Application filed December 24, 1910. Serial No. 599,212.

To all whom it may concern:

Be it known that I, WILLIAM E. FICKLEN, a citizen of the United States, and a resident of New York city, county and State 5 of New York, have invented certain new and useful Improvements in Curb-Nosings and the Like, of which the following is a specification.

My invention relates to improvements in 10 nosings for artificial stone corners and has especial and important advantages with respect to street curb nosings and the like.

While there have been devised in the past many forms of nosings for protecting corners, many of these have been wholly inapplicable and unsuited and practically inoperative when used as nosings for street curbs. And although many forms of nosings have been especially designed for street 20 curbs, these in the main have been impracticable for one or more of several reasons. A practical, efficient and durable curb nosing, I have found, should be made of a single integral bar, with especially strong and effective 25 anchoring means integral therewith. Moreover, the structure should be as simple as possible and one which may be easily and cheaply manufactured. The cost of such nosing is one of the most important elements when considering its practicability. It has to be used in great quantities, and even a small difference in the cost of manufacture resolves itself into an item of great 30 importance.

One object of my invention is to provide 35 a nosing for this purpose which can be very cheaply and easily manufactured, much more so than prior devices, and one which will have an amply strong and sufficient 40 anchoring means, this anchoring means to be integral with the nosing, thus avoiding the use of a large number of bolts or other connecting devices.

A further object of my invention is to 45 provide a suitable frog or plate for properly holding the nosing in place, while the concrete or other artificial stone is being filled in about it.

A further object of my invention is to 50 properly coat these plates, preferably by galvanizing them, so as to prevent rusting during shipment or before the nosings have been finally put into place.

Further objects, features and advantages 55 will more clearly appear from the detailed description given below, taken in connec-

tion with the accompanying drawings, which form a part of this specification.

In the drawings, Figure 1 is a perspective showing one form of my improved street curb nosing. Fig. 2 is a perspective showing a nosing similar to Fig. 1. Fig. 3 is a perspective showing a portion of a curb, partly in section, showing my improved frog or supporting plate and the nosing in place thereon.

Referring more especially to Figs. 1, 2 and 3, 1 represents a "bull-nosed" T-bar, having top lateral webs 2 and 3 with a central web 4. By "bull-nosed," I mean that the top portion formed by the webs 2 and 3 is thicker than the central web 4, that is, the top portion is relatively thick opposite and as compared with the central web 4, and tapers toward the outer edges of the webs 2 and 3. This top portion formed by the webs 2 and 3 is preferably curved, as shown to conform to the lines of the curbing and to render the same more efficient in service. The central web 4 is sheared out 70 along a line running lengthwise of the web as at 5, the portions sheared out being bent outwardly as at 6 and the bent out portions 6 having their outer ends bent over or hooked as at 7 to form an extremely strong 75 and secure anchoring means. It will be readily understood that the nosings as shown in Figs. 1 and 2 are merely short 80 lengths and in actual practice the bars are made in much longer lengths with a plurality of anchoring means 6 sheared out 85 from each bar.

In putting the nosings in place, I provide 90 a frog or supporting plate 8, having a portion of its top edge as at 9 extending to the top of the curbing and a portion of its side edge 10 extending to the front of the curbing. Plate 8 also has apertures 9' therein, to securely anchor the same within the concrete or the like. Plate 8 also has a cut 95 away portion as at 11, which is designed to engage the sides of the central web 4 of the nosing 1 and support the nosing in place while the concrete is being filled in about 100 the same to form the curb. The plates 8 are 105 cut away as at 12 in order that these portions of their edges may not be exposed when the curb is finished. The frogs or plates 8 and the whole of the nosings 1 are 110 coated with a suitable coating to prevent them from rusting before they are finally put into place. For this purpose they may

1,032,393

be dipped in shellac or a high grade of asphaltum, but I preferably galvanize all forms, as this has many advantages over the other methods.

5. Although I have described my improvements in great detail, nevertheless I do not desire to be limited to such details except as clearly specified in the appended claims.

Having now fully and clearly described 10 my improvements, what I claim as new and desire to secure by Letters Patent, is:

10. A nosing for corners of artificial stone, comprising an integral T-bar having portions of its central web sheared away on a line running lengthwise of the nosing and bent out substantially in the same plane with the central web.

2. A nosing for corners of artificial stone, comprising an integral T-bar having portions of its central web sheared away on a line running lengthwise of the nosing and

15 bent out substantially in the same plane with the central web, said bent out portions having their outer ends bent over or hooked, to more securely anchor the nosing in place.

3. A nosing for corners of artificial stone, comprising an integral T-bar having portions of its central web sheared away on a line running lengthwise of the nosing and bent out substantially in the same plane with the central web, said bent out portions having their outer ends bent over or hooked, to more securely anchor the nosing in place.

bent out substantially in the same plane with the central web, said bent out portions having their outer ends bent over or hooked, to more securely anchor the nosing in place.

3. A nosing for corners of artificial stone, comprising an integral T-bar having portions of its central web sheared away on a line running lengthwise of the nosing and bent out substantially at right angles to the general direction of the nosing, and substantially in the same plane with the central web, said bent out portions having their outer ends bent over or hooked, to more securely anchor the nosing in place.

In testimony whereof, I have signed my name to this specification, in the presence of two subscribing witnesses,

and have caused WILLIAM E. FICKLEN,

Witnesses: GORHAM CROSBY, EDWIN SEGER,

and have caused the same to be signed under

and affixed thereto and dated the day and year

and place whereon the same was signed, and
